STERILIZING APPARATUS

Frank L. Irish, De Witt, and Samuel Feldman,
Syracuse, N. Y.

Application September 11, 1946, Serial No. 696,166

5 Claims. (Cl. 21—83)

1

This invention relates to an improved sterilizing apparatus of the type wherein articles are stored and sterilized preferably by exposure to disinfecting or germicidal fumes.

This invention relates more particularly to a cabinet for storing and sterilizing one or more electric hair clippers or analogous instruments having electric cords or the like which are permanently attached or not readily detachable.

Although the electric hair clipper is reputed to be a source of trouble as a germ-carrying agent, satisfactory sterilizing means have not been available due to the clumsy shape and the size variations of such clippers and especially due to the presence of the electric cord attached to the clipper.

The principal object of this invention is to provide a durable sterilizing cabinet of inexpensive construction for conveniently and efficiently storing and sterilizing a number of instruments, such as electric hair clippers, without injury to the instruments or interference with their cords.

Further objects and advantages of the invention will be clear from the following description of the preferred embodiment of the invention shown in the accompanying drawings.

In the drawings:

Figure 1 is a sectional view through the cabinet taken on the line 1—1 of Figure 2, showing one instrument supporting panel in the "in" position and one in the "out" position;

Figure 2 is a front elevation of the cabinet showing both panels in their "in" positions and showing in broken lines the exterior portions of the cords of two electric hair clippers as they appear when the instruments to which they are attached are being stored and sterilized within the cabinet;

Figure 3 is a front view of a panel removed from the cabinet and showing in broken lines an electric hair clipper attached thereto;

Figure 4 is a sectional view of the cabinet taken on the line 4—4 of Figure 1, showing in broken lines a clipper in place on the panel which is in the "out" position in Figure 1;

Figure 5 is a sectional view of the cabinet taken on the line 5—5 of Figure 1, showing in broken lines a clipper in place on the panel which is in the "in" position in Figure 1;

Figure 6 is a detail sectional view taken on the line 6—6 of Figure 4;

Figure 7 is a detail sectional view taken on the line 7—7 of Figure 5; and

Figure 8 is a detail sectional view taken on the line 8—8 of Figure 1.

The cabinet 10 enclosing the storage and sterilizing chamber 11 comprises a base 12, a casing 13, and a plurality of instrument supporting panels 14 (in this instance, two) rotatably

2

mounted on the casing 13. The base 12 is adapted to be removably positioned on a marble counter or like supporting surface. The casing 13 fits over and is detachably secured to the base 12, the casing 13 being thereby held rigidly in upright position. The rotatable panels 14 are provided with means for temporarily attaching thereto electric hair clippers or the like, and, by rotating the panels, the clippers may be located either within the chamber 11 for storage or sterilizing, or on the outside of the cabinet for easy removal and use.

The casing 13 is preferably formed by casting it in one piece, and includes a front wall 15, side walls 16, a rear wall 17 and a top 18. The lower portions of the walls 15, 16 and 17, adjacent the base 12, extend substantially vertically, and the upper portions of these walls and the top 18 are rounded and inclined as illustrated, in order to provide a graceful appearing cabinet and to permit casting of the casing 13.

The base 12, preferably also a casting, is shaped to fit within the lower portion of casing 13 and has a front wall 20, a rear wall 21 and side walls 22. Base 12 is provided with two raised dome-shaped portions 23, shown in Figures 1 and 5, which are located substantially midway between the front and rear of base 12 and each adjacent a different one of the side walls 22. Each dome portion 23 receives a rubber suction cup 24 which is fastened to base 12 by a screw 25 and a wing nut 26 for securely but detachably anchoring base 12 to a supporting surface. A container 27, preferably in the form of a tray, as shown, adapted to hold an evaporating sterilizing agent such as formaldehyde solution, is placed on the central portion of base 12 to effect sterilization within the chamber 11. If desired, however, any other suitable sterilizing agent may be employed, such as a bactericidal electric lamp (not shown) which could be mounted within chamber 11. The front wall 20 of base 12 is inclined upward and rearward so that casing 13 may be readily placed over or removed from base 12 as herein-after described. Casing 13 is removably secured to base 12 by two pins 28, riveted or otherwise fixed to rear wall 21 of the base 12 behind domes 23, and by a spring latch 29 fastened by screw 30 to the inside of front wall 20 of the base at its center. Bores 31 drilled in rear wall 17 of the casing 13 receive the pins 28 while latch 29 clips over a ledge 32 formed on the inside of the front wall 15 of casing 13.

Each panel 14 is provided with an upper flange 35 and a lower flange 36, both extending the entire width of the panel. An upper pivot pin 37 is secured to flange 35 medially of the panel by a screw 38, and journals in a bore 39 in the top 18 of the casing. A lower pivot pin 40 is rigidly fixed at one end in a recess 41 formed in flange 36

medially of the panel 14. Flange 36 rests on a sill 42 formed in the lower portion of front wall 15, which sill is provided with a bore 43 in which pivot pin 40 is journaled. The panels 14 are thus mounted for rotation medially of their sides.

The clipper holding means for each panel 14 are arranged to face outward when the panel is in its "out" position. Each panel is provided with a loop 45 located near the top and a fork 46 located near the bottom of the panel, both adjustably held to the panel as by set screws 47. The loops 45 and the forks 46 are provided with rubber or like protective coverings 48 and 49, respectively, and a recess 50 is provided in the face of each panel for receiving a protective pad 51, preferably of felt. These holding means permit rapid insertion and removal of the clipper 52 without injury to the instrument and permit quick adjustment for clipper size and shape variations.

In order to accommodate the electric cord of the clipper and to permit the panel to be rotated from its "out" to its "in" position and back without interference with the electric cord, an open channel 60 is provided longitudinally through the lower pivot pin 40. The channel 60 is open at the same side of the panel 14 on which the clipper holding means are located, so that the electric cord 61 of the clipper 52 may be freely received therein, as best shown in Figure 3. The recess 41 in the flange 36 in which the pivot pin 40 is secured must of course also be open at the edge of the flange 36 as illustrated, so as not to block the channel 60. Also, the portion of front wall 15 adjacent the bore 43 must be provided with an opening 62 registering with the channel 60, as best shown in Figures 2, 6, and 7. A recess 63 is provided centrally of the front wall 15 immediately below the sill 42 and the bore 43 in order to permit easy egress of the cord 61 from the lower end of the channel 60. By virtue of this construction, the electric cord 61 depending from the clipper 52 may be inserted laterally through the opening 62 into channel 60 when the panel 14 is in its "out" position, and when the panel is rotated to its "in" position, the clipper 52 and the upper portion of its cord 61 will be carried into the chamber 11 while the remainder of the cord 61 extends through the pivot pin 40 to the outside of the cabinet.

On the clipper supporting side of each panel 14, two notches 65 and 66 are formed in flange 36, each notch located adjacent a different side of the panel. Adjacent the lower end of each panel, a stop pin 67 is fixed in and projects upward from sill 42, as shown in Figures 1 and 8. The stop pin 67 engages with notch 65 in the cooperating panel 14 when the panel is in its "out" position and with notch 66 when the panel is in its "in" position. These stop means limit the rotary movement of the panels 14 to 180° and provide full closure at each limit of rotation. Due to the inclined position of the panels 14, the weight of a clipper mounted on a panel 14 tends to hold the panel closed, and sealing strips 68, preferably of rubber, are fixed to the inside of front wall 15 and extend around each of said panels to further insure a tight seal.

In the use of the invention, base 12 is placed upon a supporting surface, preferably between two barber chairs so that the electric hair clippers are readily available to each barber. After the suction cups 24 have been adjusted to grip the supporting surface, tray 27 is provided with a sterilizing agent and placed on the central por-

tion of base 12. Casing 13 is placed over base 12 in a rearwardly tilted position so as to locate the pins 28 within the bores 31. Casing 13 is then swung forward and down until latch 29 snaps over ledge 32. Casing 13 may be released from base 12 by reaching through the opening for a panel 14, disengaging latch 29 from ledge 32, and then tilting casing 13 rearward until pins 28 can be disengaged from bores 31. When casing 13 has been secured to base 12 and the panels 14 rotated to their "out" positions, the clippers may be mounted on the panels as shown in Figure 4, any necessary adjustment of loops 45 and forks 46 being made by means of the set screws 47. To store or sterilize the clippers within the chamber 11, the panels 14 are rotated 180° to their "in" positions, as shown in Figure 5. The clippers positioned on the panels 14 are thus carried into chamber 11, and the channelled pivot pins 40 carry the upper portions of cords 61 inside of the cabinet while permitting the lower portions of the cords to extend from the inside to the outside of the cabinet through channels 60 and recesses 63, without either cord interfering with the other. The free ends of the cords 61 may be provided with plugs and thus connected to suitably located conventional power outlets in the usual manner. It will be observed that the clippers are readily available, singly or together, without interfering with each other, merely by rotating one or both of the panels 14 180° to their "out" positions.

The chamber 11 is substantially sealed with the panels 14 in either "in" position or "out" position. The lower panel flange 36 and the sill 42 are so shaped, as best seen in Figures 1 and 8, as to provide close sealing contact therebetween in either position of panel closure, except at the pin 40. When a panel is in its "out" position, the channel 60 of the pin 40 is entirely outside of the chamber 11, as best shown in Figure 4, and hence no leakage of sterilizing fumes can then occur through the pin 40. When a panel is in its "in" position, the chamber 11 is in communication with the outside air through the channel 60, as best shown in Figure 5, but the channel 60 is then ordinarily almost closed by the cord 61, as illustrated in Figure 7. If desired, the cords 61 may be provided with suitable soft rubber grommets to seal the lower ends of the channels 60 when the clippers are in place on the panels 14.

Although, in accordance with the patent statutes, we have thus described our invention in detail in the best form in which it is known to us, it will be evident to those skilled in the art that changes and modifications may be made without departing from the spirit of the invention. We desire to be limited, therefore, only by the scope of the appended claims.

We claim:

1. In an apparatus for accommodating at least one instrument having an attached electric cord or the like, a cabinet forming a substantially sealed chamber; said cabinet having a panel mounted for rotation medially of its sides; means on said panel for holding a cord-carrying instrument with its cord depending; means on the lower end of said panel for receiving the upper portion of the instrument cord; said panel being so constructed and arranged as upon rotation in one direction to carry said instrument and said upper cord portion into said chamber while permitting the cord to extend from inside to outside of said cabinet, and as upon rotation in the other direction to carry said instrument and said upper

cord portion outside of said cabinet so as to be readily accessible for immediate use.

2. In an apparatus for accommodating a plurality of instruments having attached electric cords or the like, a cabinet forming a substantially sealed chamber; said cabinet having a plurality of panels mounted for rotation medially of their sides; means on said panels for holding cord-carrying instruments with their cords depending; means on the lower ends of said panels for receiving the upper portions of the instrument cords; said panels being so constructed and arranged as upon rotation in one direction to carry said instruments and said upper cord portions into said chamber while permitting the lower ends of said cords to extend from inside to outside of said cabinet, and as upon rotation in the other direction to carry said instruments and said upper cord portions outside of said cabinet so as to be readily accessible for immediate use; and means cooperating with said panels to limit the rotation of each panel to substantially 180°; said panels being operable independently and arranged so that said instruments and said cord portions are spaced from one another to avoid interference therebetween as said panels are rotated from one position to the other position.

3. In an apparatus for accommodating at least one instrument having an attached electric cord or the like, a cabinet forming a substantially sealed storage and sterilizing chamber; sterilizing means within said cabinet; said cabinet comprising a base and a separable casing; said cabinet having a panel mounted on said casing for rotation medially of its sides; means on said panel for releasably holding a cord-carrying instrument with its cord depending; means on the lower end of said panel for releasably receiving the upper cord portion of the instrument cord; means cooperating with said panel to limit its rotation to substantially 180°; said panel being so constructed and arranged as upon rotation in one direction to carry said instrument and said upper cord portion into said chamber for storage and sterilizing while permitting the lower end of said cord to extend from inside to outside of said cabinet, and as upon rotation in the other direction to carry said instrument and said upper cord portion outside of said cabinet so as to be readily accessible for immediate use; and said cord receiving means being so constructed as substantially to prevent the escape of air from said chamber when said door panel is in either position of closure.

4. In an apparatus for accommodating at least one instrument having an attached electric cord or the like, the combination of a vertically disposed cabinet forming a substantially sealed storage and sterilizing chamber; said cabinet comprising a casing and a base; means for securing said casing removably to said base; suction cup means for anchoring said base to a substantially horizontal supporting surface; a container in said chamber for holding a sterilizing agent for generating sterilizing fumes; a panel mounted on said casing for rotation medially of its sides and adapted to close an opening in said casing; means cooperating with said panel to limit its rotation to substantially 180°; sealing means around the inside edge of the panel opening; ad-

justable holding means on one side of said panel for releasably holding said instrument; said panel being characterized by the provision of a lower pivot pin having a cord receiving channel along its length; said pin being rigidly fixed to the lower portion of the panel for rotation therewith; the lower portion of said pin being journaled in the lower portion of said casing; said pin in combination with said panel being so constructed that when said panel is rotated to its "out" position, said instrument may be positioned in said instrument holding means and its upper cord portion may be releasably inserted in said channel, and that when said panel is rotated to its "in" position, said instrument and its upper cord portion will be carried from outside to inside of said cabinet, while permitting the cord received in said channel to extend from inside to outside of said cabinet; and said pin being so constructed as substantially to prevent the escape of air from said chamber when said panel is in either position of closure.

5. In an apparatus for accommodating a plurality of instruments having attached electric cords or the like, the combination of a vertically disposed cabinet forming a substantially sealed storage and sterilizing chamber; said cabinet comprising a casing and a base; means for securing said casing removably to said base; suction cup means for anchoring said base to a substantially horizontal supporting surface; a container in said chamber for holding a sterilizing agent for generating sterilizing fumes; a plurality of panels mounted on said casing for rotation medially of their sides, each panel being adapted to close an opening in said casing; means cooperating with said panels to limit their rotation to substantially 180°; sealing means around the inside edges of the panel openings; adjustable holding means on one side of each panel for releasably holding one of said instruments; each of said panels being characterized by the provision of a lower pivot pin having a cord-receiving channel along its length; each pin being rigidly fixed to the lower portion of the panel for rotation therewith; the lower portion of each pin being journaled in the lower portion of the casing; said pins in combination with said panels being so constructed that when a panel is rotated to its "out" position, one of said instruments may be positioned in said instrument holding means and its upper cord portion may be releasably inserted in said channel, and that when said panel is rotated to its "in" position, said instrument and its upper cord portion will be carried from outside to inside of said cabinet, while permitting the cord received in said channel to extend from inside to outside of the cabinet; said pins being so constructed as substantially to prevent the escape of air from said chamber when said panels are in either position of closure; and said panels being so constructed as to be operable independently, whereby said instruments and said cords are prevented from interfering with each other, and whereby one instrument may be rotated to "out" position for use, while another instrument is in the "in" position for storage and sterilizing.
